ALEXANDER C. MUNRO, OF BRITANNIA BEACH, BRITISH COLUMBIA, CANADA

BALL FORMING MACHINE

Application filed January 9, 1930. Serial No. 419,818.

This invention relates to improvements in machines for forming balls or bodies of approximately spherical form and consisting of steel or similar material. Such balls are extensively used at the present time, for example in crushing mills, and the purpose of the present invention is to provide improved means for forming such balls from suitable stock; for example, used railroad rails or other steel rail or bar material.

The main object of the present invention is to provide a machine which is adapted to form the balls by a rolling operation and to cut off the balls at the proper stage in the forming operation in such manner that the severing of the balls is performed sharply and definitely, thereby increasing the efficiency of the operation and improving the form and finish of the balls.

The accompanying drawing illustrates the improvement of my invention and relating thereto:

Fig. 1 is a side elevation of the machine partly in section.

Fig. 2 is an end elevation of the machine.

Fig. 3 is a section on line 3—3 in Fig. 1.

Fig. 4 is a transverse section of the forming rolls at the cut-off point.

The machine comprises an upper roll 1 and a lower roll 2 mounted respectively on shafts 3 and 4 journaled in suitable bearings 5 and 6 on standards 7 and 8 in the usual manner of machines of this kind, the bearings being mounted, for example, in guideways in said standards and adjusted by shims 9 and screw 10 so as to provide for adjustment of the distance apart of the rolls and for firm support of the rolls during the forming operation.

Suitable means are provided for driving the rolls 1 and 2, for example, a driving gear 12 carried by a driving shaft 13, mounted in a fixed bearing and engaging gear wheels 14 and 15 respectively on the shafts 3 and 4 of the rolls 1 and 2, so as to operate said rolls in the same rotative direction and at substantially the same rotative velocity.

A guide passage or feed opening 16 is provided in standard 8 for guiding the stock indicated at 18 into position between the rolls,

and guide means 19 are provided extending between the standards 5 and 6 and secured thereto so as to guide the stock or work in its passage between the rolls, these guide means 19 extending in the reentrant angle between the roll surfaces at each side of the axis of the machine, which is also the axis of the feed passage 16. A delivery passage 20 is formed in the standard 5 leading to a discharge chute 21 for delivering the formed balls to any suitable receiving means.

Each roll, 1 and 2, is formed with a helical rib or flange extending from end to end thereof said rib forming a series of spaced convolutions about the body of the roll. In the initial portion of each roll, this rib, as indicated at 22, is of gradually increasing height, so as to provide for gradual intrusion of the rib into the material of the stock for progressive formation of the balls. At a certain portion thereof, for example, at about mid-length of the roll this rib is provided on one of said convolutions with an enlarged portion 23 or projection extending around the roll through a minor portion of its circumference acting as a cut-off or knife for suddenly severing the formed ball. This knife portion may be formed on or secured to the flange or rib in any suitable manner, for example, by welding it onto the flange. The flange or rib portion 24 succeeding the knife portion 23 may be of uniform height as shown, or if desired, may be varied in height in any suitable manner, the function of these flange portions being to finish and smooth the ball and deliver it to the delivery means 20. The flange or rib portions 24 are shown as increasing in pitch toward the delivery end, but the said flange or rib portions 24 may, if desired, be of uniform pitch.

The lateral guides 19 are preferably provided with notches indicated at 25 at a portion thereof which is opposite the knife portions on the ribs so that as the rolls rotate the said knife portions will traverse said notches in the guide means 19.

In the operation of the machine the stock, indicated at 18 is fed forwardly through the passage 16 into the space between the rolls and is then subjected to a forming operation be-

tween the adjacent faces of the rolls. By reason of the rotation of the rolls in the same rotative direction these adjacent faces of the rolls move in opposite linear directions with the result that there is relatively little, if any, lateral force exerted on the stock; but the flanges or ribs tend to score or groove the stock on opposite sides and to rotate the stock so as to cause circumferential grooves to be formed in the stock, the spacing of the grooves corresponding to the spacing of the ribs on the rolls and the grooves being progressively deepened as the stock is fed forwardly by the rolls, this feeding operation being also effected by the helical flanges or ribs. When the work reaches the portion of the rolls occupied by the knife means 23, it is suddenly and completely severed by the operation of said knife means. I have found that when it is attempted to twist and cut off the balls without the use of such knife means, the wear on the ribs is excessive apparently by reason of the increasing greater peripheral diameter of the ribs which causes the ball stock to be twisted unduly before being severed, and the provision of the knife means avoids this difficulty. After leaving the knife means the balls are finished in the groove portions of the rolls at the delivery end thereof, so as to smooth and finish the ball, the ball being finally delivered to the delivery means 20.

I claim:

In a ball forming machine, a pair of rolls having parallel axes, means for driving each roll in the same rotative direction, each roll having a helical rib formed thereon and increasing gradually in depth from one end of the respective roll toward the other end thereof, said rib forming a series of spaced convolutions about the body of the roll, one convolution on each roll having a projection extending around the roll through a minor portion of its circumference, the projections of the two rolls being arranged to oppose each other once during each revolution of the rolls.

In testimony whereof I have hereunto subscribed my name this 20th day of Dec., 1929.

ALEXANDER C. MUNRO.
